DEVICE FOR LOCKING TOUCH TONE TELEPHONES

John K. Roof, Sun City, Ariz., assignor to Woodrow T. Morrow, Paradise Valley, Ariz.

Filed Apr. 18, 1972, Ser. No. 245,292

Term of patent 14 years

Int. Cl. D14—03
U.S. Cl. D26—14 A

FIG.1.

FIG.2.

FIG. 1 is a perspective view of the front, right side and top of the device for locking touch tone telephones, with the back of a telephone receiver shown in dash lines for purposes of illustration of where said device will be mounted on a telephone; and

FIG. 2 is a perspective view of the back, bottom and other side of the device shown in FIG. 1.

I claim:

The ornamental design for the device for locking touch tone telephones, as shown and described.
